UNITED STATES PATENT OFFICE.

FREDERICK SCHWARTZ, OF NEW YORK, N. Y., ASSIGNOR TO ROBERT FINDLAY MANUFACTURING CO., OF NEW YORK, N. Y., A CORPORATION OF NEW YORK.

DESIGN FOR A LIGHTING-FIXTURE.

54,715.

Specification for Design.

Patented Mar. 16, 1920.

Application filed March 2, 1918. Serial No. 220,064. Term of patent 7 years.

To all whom it may concern:

Be it known that I, FREDERICK SCHWARTZ, a citizen of the United States, residing at New York, in the county of Kings and State of New York, have invented a new, original, and ornamental Design for a Lighting-Fixture, of which the following is a specification, reference being had to the accompanying drawing, forming part thereof.

Figure 1 is a perspective view of a lighting fixture, comprising a lower translucent light diffusing bowl, substantially as shown in the drawing. Just above the bowl is sus-

pended a shade the inner surface of which is covered with a plurality of prismatic configurations of transparent glass over a silvered reflecting surface, although it is apparent that any desired reflecting media can be employed.

Fig. 2 is an inverted plan view of the shade.

I claim:

The ornamental design for a lighting fixture, as shown and described.

FREDERICK SCHWARTZ.
